UNITED STATES PATENT OFFICE.

COLMAN A. CRENSHAW, OF SALT LAKE CITY, UTAH.

LOCK.

Application filed August 23, 1927. Serial No. 214,812.

My invention relates to locks and has for its object to provide a new and efficient lock for use in locking dwelling doors or other doors or closures where it is desired to keep 5 marauders or intruders from entering without the permission of the owner.

A further object is to provide a lock which will be efficient at all times and one which will not wear out from continued service over 10 a long period of time.

A still further object is to provide a lock which will be burglar proof and one which can be locked from within the house and can not be opened from without under any 15 circumstances, even with the correct key.

These objects I accomplish with the device illustrated in the accompanying drawings, in which similar numerals and letters of reference indicate like parts throughout the several views and as described in the specification forming a part of this application and pointed out in the appended claims.

In the drawings, in which I have shown the best and most preferred manner of building my invention, Figure 1 is a plan view of the lock. Figure 2 is a vertical section on line 2—2 of Figure 1. Figure 3 is a view of the casting forming the interior of the lock. Figure 4 is a view of the central shaft of the lock.

In the drawings, in which I have shown the best and most economical manner of constructing my invention, I have shown the cylinder in which the working parts of my invention are carried as A, with the handles or knobs as B. I provide short bosses or rods 1 radiating diametrically from said knobs by which the knobs may be turned when opening the door and which knobs are so placed so that the door may be opened when the hands are wet, soapy or slippery from grease or other sources. A central shaft 2 is provided, running from end to end of the cylinder A and into the knobs, which are secured thereto by the screws 3 which are placed in each end of the knobs and which screw into threaded holes in the extreme ends of the shaft 2. The said shaft 2 has a gear wheel 4 formed medially thereon, which gear wheel meshes with teeth 5 on a plunger 6. The plunger 6 is the means of locking the door and is adapted to have one end beveled at 7 and to fit into any of the common types of sockets secured in the door frame. Keys 8 are placed in keyways provided in the knobs and the ends of the shaft

2 to prevent slipping of the knobs on the shaft. A spring member 9 is secured on the said shaft by pins 10 and a spring stop 11 is secured to the outer cylindrical casing A by 60 which the spring is stopped from turning in either direction when the handle is being turned. The spring 9 is a coil spring and is carried between spring hinges 12 and 13, which hinges have one end of the spring engaged over each one so that the shaft may be turned in either direction as desired but will still have spring pressure to return it to normal position and the stop 11 will hold the spring and the shaft in normal position at all 65 times except when the knobs are turned and will always return the knobs and the shaft to the original normal starting position. A beveled ring 14 is provided between the knob B on one end and the end of the cylinder A and is flanged at 15 and secured to the shaft 2, with a hole 16^a therein in which the tapered end of a sliding plunger 16 is passed when locking the door. A casting member 17 is provided within the said casing A and 70 is provided with a central bore 18 therethrough, which bore is larger at one end than at the other, as at 19. The said enlarged bore 19 is surrounding the gear wheel 4 on the shaft 2, and the casting is secured in the said cylinder A by the screw 20. Two sides 75 21 and 22 of the said casting 17 are milled flat, as shown in Figure 3, and a spring shaft 23 is secured therein on one side only. A spring engaging fork 24 is then secured to 80 the plunger rod 16 by the rivet 25. The spring 26 is then placed over the shaft 23 and is the means of moving the plunger rod 16 into the hole 16^a when the rod is released. A milled slot 27 is cut in the top side of the 85 plunger rod 16 and an outside lock plunger bolt 28 is carried therein, with an offset 29 on one side of said bolt 28 which is to be moved by the key to the lock, and which is 90 slidable in the groove 30 in the side of the slot 27. The end of the said bolt 28 is tapered and is adapted to fit into a hole 31 in a beveled ring 32, which ring 32 is carried between the knob B and the other end of the cylinder A. The said ring 32 has a cylindrical member 33 formed on the inner side thereof through which the shaft 2 is passed in a hole 34, and the end of the cylindrical member 33 has a thread 35 formed thereon 95 adapted to engage with a lug 36 formed on the bottom side of the free end of the plunger rod 16 to move the said rod longitudinally 100 105 110

with the rotation of the ring 32 to disengage the locking end of the said plunger from the hole 16^a when the person is entering the house from without. A key hole 38 is provided through the side of the cylinder A and a key 39 is carried therein supported on the lower side by a bracket 40, which bracket is secured to the casting 17. The outer end of the key 39 is squared to fit any desired key and a boss 41 is provided below the cylindrical casing A adapted to engage with the offset 29 to disengage the locking bolt 28 from the hole 31. A spring 43 is secured to the casing A by the rivets 44 and the end of which is engaged in a hole 45 provided in an offset 46 near the end of the plunger bolt 28. Said spring is provided to move the bolt longitudinally to lock the door. The plunger 16 has a lug 49 formed on the top side thereof and the collar 14 has a catch lug 50 formed on one side thereof adapted to engage with said lug 49 to lock the movement of any of the parts of the lock.

The operation of my lock is as follows:—

To lock the door the plunger 6 is placed in the door socket and the plunger 28 is in the hole 31 which holds the door locked from without. The spring 9 normally holds the plunger 6 in the socket of the door and to withdraw the plunger to open the door the knobs B must be rotated compressing the spring but withdrawing the plunger. The moment that the knobs are released the spring again forces the plunger 6 out into the socket if the door is closed or into the open air if the door is open. To open the door from outside the key is placed over the top of the key 39 and the key turned. This places the member 41 against the lug 29 and when turned moves the plunger 28 longitudinally, releasing the lock and allowing the knob to be turned and the door opened. When the door is again closed it automatically locks itself by the action of the spring 26 and the fork 24. To lock the door at night to prevent any one from entering dur-

ing the night, the ring collar 14 is rotated until the plunger 16 has moved into the hole 16^a and the lug 50 is engaged over the lug 49 which locks the door from any one entering from without, whether he has the correct key or not. To release the lock the collar ring 14 is turned in the opposite direction until the plunger is free of the hole 16^a. The door may then be opened.

Having thus described my invention I desire to secure by Letters Patent and claim:—

1. In a door lock the combination of a cylindrical casing, a central shaft therethrough; a collar over each end of said casing, there being a hole in each collar adapted to have a plunger passed therein; coacting plungers carried one within the other within said casing; springs to actuate said plungers independently; means to actuate said plungers by a key; a knob on each end of said central shaft; a spring member on said central shaft to allow said shaft to rotate partially in either direction; a gear wheel on said shaft; a plunger 6 having gear teeth thereon adapted to fit the teeth of said gear and to mesh therein; and a casting within said casing in which the shaft and parts are carried and operated.

2. In a door lock the combination of a cylindrical casing; a casting within said casing; a central shaft through said casing and casting; a gear wheel on said casting; a plunger having teeth thereon operable at right angles to said shaft; coacting plungers one within the other carried in said casting and controlled by separate springs; a coil spring to control the movement of said shaft; collars over the end of said casting having plunger holes therein in which said coacting plungers are placed when the door is locked; and means to move and control the movement of said plungers as desired.

In testimony whereof I have affixed my signature.

COLMAN A. CRENSHAW.
